[57] CLAIM

The ornamental design for a carafe, as shown and described.

DESCRIPTION

FIG. 1 is an elevational view of a carafe showing my new design;

FIG. 2 is a top plan view;

FIG. 3 is a bottom plan view; and

FIG. 4 is a fragmentary sectional view taken on the line 4—4 of FIG. 1.

The arcuate depressions seen in FIG. 1 extend around the lip in the spaced-apart relationship indicated.

Fig. 1.

Fig. 2.

Fig. 3.

Fig. 4.
